UNITED STATES PATENT OFFICE.

ARTHUR E. DULMAGE, OF OBERLIN, OHIO, ASSIGNOR TO BUCKEYE CREAM SEPARATOR CO., OF SAME PLACE.

DESIGN FOR A COVER FOR CANS.

SPECIFICATION forming part of Design No. 30,672, dated May 2, 1899.

Application filed April 10, 1899. Serial No. 712,544. Term of patent 7 years.

To all whom it may concern:

Be it known that I, ARTHUR E. DULMAGE, a citizen of the United States, residing at Oberlin, in the county of Lorain and State of Ohio, have invented and produced a new and original Design for Covers for Cans, of which the following is a specification, reference being had to the accompanying drawing, forming part thereof.

In the drawing my design is shown in a perspective elevation of the cover itself as a complete article; and the leading feature of the design consists in the configuration or outlines of the cover as a whole. In this outline several features are conspicuous, and notably the converging and inclined lines 2, on which the central portion or body of the design is fashioned and which is decorated centrally at its top with a pinnacle 3, and upon or in which is displayed what appears like a webbing of

fine figure-work 4. The edge of the cover is defined by an outwardly-extending border 5, in the base of which the inclined lines 2 are merged or absorbed, and beneath the said border is a skirting 6, having a plain surface and depending, as appears, from the inner edge of the border 5. Ring-shaped ornaments 7 on opposite sides, though not conspicuous in themselves, serve to afford some relief to the otherwise plain top surface of the design, except as it is relieved by the central pinnacle 3.

What I claim is—

The design for a cover for cans, substantially as herein shown and described.

Witness my hand to the foregoing specification this 7th day of April, 1899.

ARTHUR E. DULMAGE.

Witnesses:

W. B. BEDORTHA,
BERTHA ECKERT.
